UNITED STATES PATENT OFFICE.

ARTHUR MOUNTFORD, OF EAST LIVERPOOL, OHIO, ASSIGNOR TO THE HOMER LAUGHLIN CHINA COMPANY, OF EAST LIVERPOOL, OHIO, A CORPORATION OF OHIO.

DESIGN FOR A COVERED DISH OR SIMILAR ARTICLE.

SPECIFICATION forming part of Design No. 36,279, dated April 7, 1903.

Application filed February 16, 1903. Serial No. 143,721. Term of patent 7 years.

To all whom it may concern:

Be it known that I, ARTHUR MOUNTFORD, a resident of East Liverpool, in the county of Columbiana and State of Ohio, have invented a new, original, and ornamental Design for a Covered Dish or Similar Article; and I do hereby declare the following to be a full, clear, and exact description thereof, reference being had to the accompanying drawing, forming part thereof.

The figure is a perspective view of a covered dish.

The leading feature of my design consists of the shape and ornamentation of the covered dish or similar article, substantially as shown in the accompanying drawing.

In the drawing, 1 denotes the dish or similar article, having the curved body portion 2, under which is the base 3 and connecting said body portion 2 by the curved line 4, while the bottom edge 5 of said base 3 is formed of the waved line 6, and above which and extending out in relief on said base 3 and around the same is the waved line 7. An ornamental handle 8 is formed on each side of the body portion 2, around the inner portion of which and extending out in relief on said portion 2 is the leaf or ornamentation 9. Extending around the body portion 2 in relief is the

border-line 10, which is provided with the small scroll fleur-de-lis 11 therein, and said portion 2 is also provided with the tooth-border 12, extending in relief around the same, while between these lines 10 and 12 and extending out in relief of said portion 2 is the floral wreath 13, which is formed of the Greek cording 14, having at each end thereof a honeysuckle 15, and between the ends of the honeysuckles is a Greek star 16. The cover 17 is provided with like borders 10 and 12 and with the floral wreath 13, and such cover also bears an ornamental handle 18, having around the same in relief on the said cover 17 the leaf ornamentation 19.

The ornamental border-lines 10 12 and floral wreath 13 can be applied to plates, cups, saucers, pitchers, and similar articles.

What I claim is—

The ornamental design for a covered dish or similar article, substantially as shown and described.

In testimony whereof I affix my signature in presence of two witnesses.

ARTHUR MOUNTFORD.
